(57) **CLAIM**

The ornamental design for a solar light tower control user interface, as shown and described.

DESCRIPTION

FIG. 1 is a perspective view of the solar light tower control user interface;

FIG. 2 is a rear view of the solar light tower control user interface shown in FIG. 1;

FIG. 3 is a top view of the solar light tower control user interface shown in FIG. 1;

FIG. 4 is a bottom view of the solar light tower control user interface shown in FIG. 1;

FIG. 5 is a right view of the solar light tower control user interface shown in FIG. 1; and,

FIG. 6 is a left side view of the bottle solar light tower control user interface shown in FIG. 1.
